Continuation of application Serial No. 504,501,
December 24, 1930. This application July 12,
1933, Serial No. 680,036

6 Claims. (Cl. 235—60)

It has been the practice since the Goldberg Patent 765,774 (of July 26, 1904), or longer, to rotate a master wheel differently by means of nine digit-keys, and to cause the master wheel 5 to operate accordingly a succession of dial-wheels, and make provision for carrying-over from each dial-wheel to the one of next higher denomina-
tion.

At about the date of said patent, the practice 10 was adopted of connecting two master wheels together, thereby to operate two totalizers by means of one differential mechanism and one set of keys. Thus, at the operation of one key, a number could be added in two columns at once.

15 In an attempt to increase this advantage, it was sought to introduce a third master wheel with a third totalizer, so that at the operation of a key a number could be added in three columns at once. But it was found that the diffi-
culty which arose from the use of two master wheels, was prohibitively increased when it was attempted to use three. This difficulty was due to the use of the numerous trains of carry-over mechanism, many or all of which would occa-
sionally operate simultaneously.

20 If a totalizer contained nine dial-wheels with eight trains of carry-over mechanism, it would require the operator to press the key hard enough to operate twenty-four trains of carry-over mechanism at once, eight trains in each of the three totalizers. This was found to be excessive, and the fault developed that the key would not overcome the resistance and become fully depressed, and the machine would therefore make a mistake. In 25 the intervening years, many ways have been attempted to overcome this carry-over difficulty, but none has been found.

This invention does not relate to improvements in carry-over mechanism. It does not at-
tempt to increase the number of master wheels 30 that can be operated by the stroke of a key.

This invention deals with modern complicated accounting, and one feature relates to the provision for vertical addition (one by one) of 35 the amounts typed in a great number of original columns, together with provision for simultaneously adding or subtracting, in the performance of one or more extra computations, any amount that is typed in any original column.

40 Sometimes it is desired to add in one column, and simultaneously either add or subtract in performing half a dozen other computations, the latter serving for cross-addition, and for dis-
tributive and other accounting purposes. It may 45 be desired, when typing a number in the next

original column, perhaps to cross-subtract in the performance of two or three of the other computations, and to cross-add in two or three still other computations. Demand for practically un-
limited flexibility of operation in an accounting 5 machine has been incessant for a score of years, but the want has not heretofore been satisfied. Accounting of this class has heretofore been done by pen-and-ink methods.

The present invention is a unitary machine 10 which employs a single set of nine digit-keys and a differential mechanism operated thereby, and also a master wheel that is controlled by said differential mechanism. It is fitted to use nu-
merous column-totalizers, which may be oper- 15 ated one after another by said master wheel, to do a small part of the single-page accounting. Said nine keys, together with a zero key, con-
stitute a single complete set of numeral-keys.

This invention presents the valuable novelty 20 of contriving to cause the same single set of keys to automatically set auxiliary indexing pins or devices, for use in a deferred computation or computations.

When a key is depressed to turn the master 25 wheel, a corresponding index-pin is also set; that is to say, if the master wheel is turned five steps by the key, the same key will operate mecha-
nism to also set an auxiliary "5" pin. These 30 pins are set one after another, as the master wheel progresses along the row of dial-wheels. The key-rotated dial-wheel has the same de-
nomination as the set index-pin, or, in other words, the denominations of the set pins corre-
spond to the denominations of the already ac- 35 tuated dial-wheels.

Every set pin remains set throughout the opera-
tion by the master wheel of the remaining dial-
wheels in that column-totalizer. At the conclusion 40 of the operation of the single set of ten keys, the whole number is exhibited in said column-total-
izer, and is also represented by the set-up aux-
iliary index-pins.

The master wheel computation having been 45 concluded, the selected auxiliary index-pins still remain set up and ready for subsequent or de-
ferred computation. Then a set of auxiliary dial-wheels is power-operated under the control of those prepared or set-up index-pins, but dur-
ing this auxiliary computation the master wheel 50 and its dials remain stationary.

There is illustrated a large number of de-
ferred-operation or auxiliary registers, and in-
dex-pins for any or all of them may be selec-
tively set in the described manner, simultane-

ously with the operation (by the ten keys and the master wheel) of only a single column-totalizer. Thus the same amount that is added in any one original column by the master wheel, may be 5 either added or subtracted in a variety of auxiliary computations, before the selected indexing pins or devices are restored to their normal idle positions.

Opportunity is afforded for a wide selection of 10 pin-indexed registers for the described deferred co-operation with any selected single vertical totalizer; thus affording opportunity for adding in any single original column while selectively entering or distributing the same amount in a great 15 variety of automatically selected auxiliary registers, either additively or subtractively. At the typing of each amount and the entry thereof into any selected column-totalizer, the described distribution or allotment of such amount may 20 proceed in a different automatic selection of deferred computation registers.

The invention has novel capacity for performing not only cross-addition to meet the utmost known demand, but also for effecting the distribution automatically among a large number 25 of auxiliary totalizers the number that is entered by the master wheel in a single vertical totalizer, and also in entirely different automatic distribution of the number that is entered in the succeeding 30 vertical totalizer while typing the same in the next column, and so on, giving a different automatic distribution among many auxiliary totalizers for every vertical totalizer, and a multitude of automatic register-selections for 35 a single line of typing.

While common vertical-adding machines are capable of totalizing many columns, still they are not fit for highly complicated accounting because of their inherent lack of capacity to effect automatically the requisite variety of distributive 40 cross-computations in each line of typing, in automatically selected groups of registers, especially where a different group must be automatically selected for every column-totalizer.

It is a desideratum in this art to provide a vast 45 increase in the number of totalizers available for use in the machine, in such a way as to increase the range of combinations of register-selections. It is desired to increase the degree of all vertical and cross-adding or distributing results, by the 50 addition of totalizers to a degree far beyond the capacity of any machine heretofore known. In other words, it is desired to effect not merely an addition to the number of totalizers, but to obtain a great increase in the number of automatically 55 combinable totalizer-units, so as to make a vast increase in the number or degree of possible automatic permutations, or to increase the possible number of associations of totalizers available for vertical adding and deferred cross-footing.

It is desired, for example, to provide for triple cross-adding. That is, it is desired, during a single line of typing, (1) to add vertically in two or three totalizers and (2) cross-add the amounts, to obtain a footing of the cross-adding column, and (3) to add vertically in two or three other totalizers and (4) cross-add the amounts in a separate cross-adder to obtain a footing of the cross-adding column, and also (5) to add vertically in two or three still other totalizers and to (6) cross-add the amounts in the third cross-adder to obtain a footing of the cross-adding column, and also to (7) carry everything into another cross-adder, to serve as a grand total reg-

ister; all register-selections to be made automatically.

The desideratum is to provide a machine which will have novel capacity for an enormous number of automatically effective selective combinations of vertical totalizers and of distributors or cross-adders, to enable the performance of cross-additions of amounts that in a single line are typed and added at the same time in the vertical columns. For example, it is desired that several 10 sub-divided accountings should be separately typed side by side upon a single page, and that each account may include the single, double or triple cross-adding of its columns, and that the correctness of the various accountings may finally be verified by printing a proof sign alongside of the amount which represents the grand total of the transactions on the entire page.

I am cognizant of an example of the prior art furnished by the Kurowski Patent 1,710,775, of April 30, 1929, which is manufactured for simple vertical totalizing, by the use of a single key-driven master wheel. It does not cross-add.

I am also aware of the patent to Wahl, 1,349,024, of August 10, 1920, a common form of adding and typewriting machine having many simple column-totalizers, in which the numeral-type keys operate corresponding trains, and any train is capable of rotating a master wheel accordingly. The operation of the master wheel and the dial places a substantial burden upon the operator's finger, which is already burdened by operating the type.

The totalizers in this Wahl patent, are connected to a paper-carriage, and each totalizer has dials operable seriatim by the master wheel as the carriage steps along. Once in each revolution, the dial operated by the key must also drive the next higher dial, and the latter may at the same time carry-over to a still higher dial, 40 and so on, the key sometimes being put to the task of driving ten dials at once, with their gears and minor parts.

Also in said Wahl patent are also shown two cross-adders, each having a master wheel to drive it, this being illustrative of the prior art. These extra master wheels have to be rotated by the same type-key which is rotating the main master wheel that drives the dial of the vertical totalizer. In each cross-adder, there is frequent necessity 50 for carrying-over on several dials at once, so that it occasionally happens that at the depression of one type-key, it must rotate about 30 dials, and operate their respective fittings in addition to driving the type against the paper. There is 55 a preposterous degree of labor thus saddled upon the finger of the operator, and it frequently results in the failure of the type to make any impression upon the paper, so that the digit, which is added in three totalizers, does not appear upon 60 the sheet, thus leading to errors. The fingers of the operator are unduly wearied in overcoming the resistance due to operating three master wheels and three dial-mechanisms at every key-stroke. This slows down the work and leads to 65 commission of errors.

This peculiarity of the prior art, illustrated by the Wahl machine, that three master wheels, together with the carry-overs, must be laboriously operated at the key-stroke, would be prohibitive 70 of the use of even one extra cross-adder. There exists a demand for something to overcome the fault of the Wahl patent and other prior art, which is that undue labor is required in operating three master wheels at the type-key stroke.

I am aware of another attempt having been made to meet the requirements of the desired accounting machine, by the patent to Poole 1,487,122, of March 18, 1924, which duplicates the 5 same faults and deficiencies of said Wahl patent.

In the prior art as exemplified in said Wahl and Poole machines, there has been no provision for effecting a far larger number of combined vertical and cross-adding computations than illustrated, or for increasing the number of permutations, or for effecting a great increase in capacity and a great increase in versatility. In other words, it is impossible in the prior art, as exemplified in said Wahl and Poole machines, to 15 secure a versatility for adaptation for different uses that is far beyond any previous combined typewriting and computing machine, and therefore by said prior art machines the objects of this invention cannot be attained.

20 Wahl's machine has no provision for variable distributive action, whereby, during the progress of a single line of typing, succeeding typed and vertically added amounts may be distributed in a variety of groupings of cross-adders. That is 25 to say, it is not possible in the Wahl machine to type an amount and add it in a vertical totalizer and distribute or enter said amount into a grouping of cross-adders, and then to type another amount in the same line and add it in another vertical totalizer and distribute the same 30 into a different grouping of cross-adders from the first amount. In the Wahl patent, there is not automatic selection of different groupings of cross-adders. In the Wahl machine, it is not 35 possible to perform triple cross-adding, or quadruple or other multiple cross-adding, since in such accounting it is necessary to enter into one or more cross-adders amounts that are successively typed on the same line on the work-sheet 40 and preserve the total thereof in the first cross-adder, while adding two more amounts that are typed in said same line and preserving the total thereof in the second cross-adder while typing still two more amounts in said same line of typing, and preserving the total thereof in a third 45 cross-adder; so that said cross-adders will exhibit three cross-totals at once; and said Wahl patent is also inefficient in performing other important features of accounting set forth herein.

50 The rule of some arts, that the number of similar elements may be increased ad libitum, has not been found applicable to such machines as that of Wahl, in which the number of master wheels has not been successfully increased beyond his two highly objectionable cross-adding master wheels and the single vertical-adding master wheel.

It would be utterly impossible to perform upon 60 any of said machines the modern accounting that is depicted at either Figure 5 or Figure 6 forming part of this application, for example. Moreover, no part of either of the accountings shown at said Figures 5 and 6 could be performed upon any of said machines, nor upon any other machine known in this art. This is for the reason 65 that a part of an accounting problem cannot be performed upon one machine and retained in said machine, and another part of the same problem performed upon a different machine and retained 70 therein, while third, fourth and fifth parts of the same accounting problem are performed upon third, fourth and fifth machines and retained therein. An accounting machine of this character is not composed of a number of separable adding entities, like the cars of a freight train,

but it must be an indivisible unit, like a steam-boat. It is indispensable that a single machine must be itself capable of performing every step of the entire accounting, and must retain in itself the product of every step, while further steps are 5 being computed in the same machine; so when the end of the complicated page is reached, it yields a result consisting of only a single amount, which has been ascertained by the computations effected in numerous vertical totalizers, such 10 amounts being distributed in different ways among auxiliary registers, simultaneously with the respective entries in the vertical totalizer. Automatic accounting, such as depicted at either Figure 5 or Figure 6, for example, has never here- 15 tofore been performed, by either machine or pen.

I am aware of the Hart Patent 1,382,286, but said patent does not show how to use, say, twenty column-totalizers for securing the totals of twenty separate columns on a page, as sometimes 20 needed in the performance of the novel accounting disclosed herein. If much of the mechanism were to be removed from the Hart machine, so that the registers would be employed only for column-totalizing, its capacity would be seven 25 columns only. Hart shows no organization whereby he could add up the column-totals, and also distribute every item in every typed line among different groupings of cross-registers. If his registers are all to be employed to receive 30 amounts distributively, then the machine could not perform any vertical column-totalizing at all.

According to the present invention, there are provided nine novel Siamese digit-trains. Each of these Siamese digit-trains performs a novel 35 double function. One sub-function of each train is to rotate the master wheel the required number of steps, and the other sub-function of the novel train is to set index-pins each corresponding to the number of steps through which the 40 master wheel rotates. Each novel Siamese train moves as a unit to accomplish this double function. As many as six or seven corresponding index-pins may be set by any novel Siamese 45 digit-train, while said train operates the master wheel.

The nine novel Siamese digit-trains may be constructed in a variety of ways, and one example is shown in the drawings, which show a novel Siamese coupler that connects sub-trains 50 in a novel coordination of master-wheel-operating devices and multiple-pin-setting devices. By way of example, one sub-train may have a rod which drives a master-wheel operating cam, and also, by way of example, the other sub-train may 55 include a bar extending transversely of several nests or systems of index-pins, said bar forming part of a linkage, the linkage being operated by a downwardly thrust stem. Said master-wheel actuating rod and said pin-setting stem may be 60 pivoted to a key-actuated coupler to form in each of the novel Siamese digit-trains. But the joining of said elements by means of a coupler is not essential in all cases, inasmuch as the novel Siamese train may be otherwise formed within the 65 scope of the invention.

The coupler is illustrated as forming a portion or element of a digit-type key-lever, which both swings the type to the platen and also operates 70 the remaining members of the entire novel master-wheel-operating and pin-setting Siamese train.

The denomination-selection for both the master wheel and the several systems of digit-pins, 75

is effected by a single step-by-step carriage, under the control of said digit-keys.

The operation of the master wheel by said novel Siamese train is completed by the operation of the digit-key, but the setting of index-pins of the same value by the same Siamese train is a step which is preparatory to the subsequent running of the same amount into other registers, selected automatically for cross-addition. These cross-adding or distributive registers are idle while the master wheel and vertical totalizer are being operated. The operation of said cross-registers is deferred until after the movements of the key and master-wheel train have ceased.

The master wheel, which is operated by one end of the novel Siamese train, actuates one vertical totalizer of the great number in the machine; while the same Siamese digit-train may pre-set appropriate digit-pins for several cross-adders. Thus there is a division, some of the computation being completed at the operation of each Siamese digit-train, while the remainder of the computing is deferred until after all the index-pins are set up by the Siamese trains.

The row of vertical totalizers may be divided into a large variety of groups, and any group may compute in combination with one or more of the cross-adders, thus affording practically unlimited versatility.

In this master-wheel machine, it is rendered feasible to cross-foot most or all of the items that form every line of typing, besides performing the primary vertical adding, and also to perform double cross-adding, triple cross-adding, quadruple and quintuple cross-adding, etc., and to perform a great variety of other accounting. Much of this complex accounting has been regarded by manufacturers as presenting impossibilities, and the field of accounting machines has been limited.

Several cross-adders, distributors or assorters may be employed for concomitantly performing a great variety of computations, whenever the single master wheel is driving any one of the many column-totalizers. Thus many computational operations may be performed concomitantly with the typing of an amount upon the sheet, and without unduly burdening the keys, since the labor required for operating the cross-adder indexing devices is not appreciable.

The cross-adder indexing mechanism will act reliably for as many as five or a few more registers, when operated by numeral-keys that are throwing the type-bars to the platen and also rotating a master wheel for actuating a column-totalizer.

One of the automatic features of the invention, is that the vertical totalizers after being individually adjusted to correspond with the locations of the columns on the work-sheet will be brought seriatim by the carriage into the master-wheel zone, and the same carriage will also automatically bring a succession of correspondingly located dogs into co-operative relation with predetermined sets of denomination-jacks, for enabling the master-wheel-operating type-keys, operating through the aforesaid Siamese trains, to set up cross-indexing devices in successive denominations, for the deferred operation of the automatically selected registers. These automatic register-selecting and denomination-selecting dogs may be assigned individually to effect the desired combinations with the vertical totalizers.

75 One dog may combine with one vertical totalizer,

so as to be the means of indexing the typed amount for deferred computation in one of the cross-adders or registers. An additional dog may secure the indexing of the amount that is added in another vertical totalizer, but for deferred computation in the same cross-adder; the dogs automatically coming into play one after another during the typing in the master-wheel-operating zones, at points determined by the adjustments of the dogs.

There may for example be as many dogs as there are vertical totalizers, and they may all automatically combine said totalizers with one of the cross-registers to receive all of the amounts that are run into all of the vertical totalizers, thus obtaining a grand total. Other dogs may be automatically associated with another cross-register, for indexing therein the same amounts that are run by the master wheel into certain predetermined vertical totalizers. A third group of dogs may automatically effect combination between certain other vertical totalizers and a third cross-register, and so on. The traveling carriage is an element in combining the vertical totalizers in the master-wheel zones, with correspondingly positioned dogs, for controlling the denominations and automatically selecting the cross-registers.

The carriage with selected and positioned dogs may combine or bring into use two or more of the cross-registers simultaneously.

The carriage selects one totalizer at a time from a great range of key-driven totalizers, and cooperates with the dogs to combine with the selected totalizer any one or any number of many power-driven cross-registers.

The invention does not suffer from the necessity that when any amount is being written in a column, the vertical totalizer for that column must be at the computing zone and not elsewhere, inasmuch as the cross-adders do not travel, and inasmuch as any one or more of them may be automatically combined with the active column-totalizer.

The machine therefore embodies provision for separately totalizing the numerous columns by means of the several vertical totalizers, by the use of a single master wheel, automatically combined with means for computing the same amounts in any one or more cross-registers, none of which has to be positioned relatively to any master wheel, and none of which has to be brought to the zone being typed.

The machine, besides double cross-footing, triple cross-footing, sub-totaling and grand totaling, may perform other subsidiary accounting, as required.

It will be seen that six or more registers can be in use at once, without calling upon the keys to rotate more than one master wheel. Said wheel operates only the selected column-totalizer, while the other five or more registers are automatically selected and their index-pins set up, and then the motor turns the dials in the five registers, so that at no time is the operator burdened with finger labor, nor is there liability of faulty operation when carrying-over in all the cross-adders or distributing registers simultaneously.

Besides performing column-addition, this invention provides that the Siamese train that operates said standard master-wheel mechanism shall also actuate the indexing devices in all of the auxiliary cross-adding sets. These indexing devices for this purpose are directly connected to

said Siamese train to be pre-set concomitantly with said standard differential adding mechanism; but it is obviously immaterial, broadly considered, whether the key-levers or some other portion of the Siamese mechanism is selected for such purpose of concomitantly pre-setting the auxiliary indexing devices. Said Siamese trains also (by the use of the carriage-element thereof) are caused by the present invention to select the 10 denominations of the auxiliary indexing devices that are pre-set.

The fingering of the keys is satisfactory, since at the beginning of the key-depression, the master wheel is put in motion, and then the pin-setting device is put in motion. While the index-pin is moving, the master wheel is disconnected from the key, and all of the momentum of the hand is then utilized in completing the key-depression, insuring the completion of the setting 20 of the index-pin, and throwing the type against the platen. The operation of the master wheel, index-pin and type is thus rendered certain and satisfactory.

As one example of automatically combined 25 cross-adding and vertical-adding, the amounts written in the numerous columns may be carried into the vertical totalizers, so that each shows the footing of its own column. To cross-add at every line, the first of three cross-totalizers may 30 be operated once for each column, or say fourteen times in a single line, and at the end it will show the cross-footing. Then the vertical totalizers may be disconnected from the keys, and the first cross-footer may be set to subtraction, 35 and the cross-footing may be copied upon the work-sheet from the first cross-footer, returning the same to zero. Then the star-key may be printed at the end of each line.

At the conclusion of the page, the vertical 40 totalizers may be set to subtraction, and the first cross-footer may be disconnected. Then all of the totals may be typed on the work-sheet, so that all of the primaries will show zero; while in a second cross-footer there may be computed at 45 the same time a grand total of the whole page. This second grand total must agree with a grand total that shows in a third cross-footer, into which every one of said items has been entered as it was typed, and then the grand total may 50 be copied on the work-sheet, clearing the second and third cross-footing registers, and the correctness of the entire page of accounting may be proved by a single star.

Addition may be very readily performed in one 55 totalizer or register while subtraction is being automatically controlled in other registers. All column-totalizers may be set for addition, or all may be set for subtraction, or they may add while the cross-registers subtract.

60 The cross-footing mechanism may have automatic controls for adding in one column and subtracting in another; while in any column the cross-footer may either add or subtract, according to manual adjustment. This gives co-operative automatic subtraction for some cross-footing with hand-control for other cross-footing.

While each line is being cross-footed, it will 70 be perceived that the numerous vertical columns may be added separately by the master wheel, while the combined total of any selected group of columns may be calculated by another of the cross-footers, and at the same time the combined total of another selected group of columns may be computed in a third cross-register. At 75 the same time a fourth cross-register may be

employed for securing the total of any single column whose vertical totalizer is being used for obtaining sub-totals; while a fifth cross-register may be employed for securing the grand total of all the entries in all the columns on the work-sheet. 5

By means of the vertical totalizers, column-totals can be obtained, and simultaneously the amounts of several selected columns may be run into a grand totalizer, while other selected columns may be run into a second grand totalizer; and if desired a grand total of all the columns can be run into a third. After having typed the sheet, the operator can disconnect the grand totalizer and set the vertical totalizers for subtraction, so that he can type the total of each column at its end, and simultaneously clear each primary totalizer, without affecting any of the grand totalizers. 10 15

It may happen that some items in a line are 20 to be cross-footed separately from other items in the same line. In this invention one cross-totalizer can be used to cross-foot the amounts typed (and added) in certain columns, and a different cross-totalizer can be used to cross-foot the 25 amounts that are typed (and added) in certain other columns. At the end of each line, one cross-footer will show one cross-total, and the other will show the other cross-total. Both cross-totals may be copied upon the work-sheet. Another cross-adder may be used for computing a 30 grand total of everything on the sheet.

The kind of accounting work depicted at Figure 6, for example, cannot be performed upon the machine of said Wahl patent, or the machine 35 of said Poole patent, or the machine of said Kurowski Patent, or the machine of Hart Patent 1,382,286. Nor can the kind of accounting at Figure 6 be performed upon any two or more of said machines. Part of the accounting cannot be 40 done upon one machine and part upon another. Prior to the present invention, said kind of accounting was only mental, and was not performable automatically by pen and ink.

It will be perceived that by this invention there 45 are cured two faults of the prior art which are exemplified in said machines. The first of said faults is inherent in machines of the Wahl, Poole, and Kurowski class, the Wahl and Poole machines being inherently incapable of performing 50 cross-addition in the requisite number of totalizers simultaneously, and the Kurowski machine not even attempting to cross-add. The second of said faults is exemplified in machines of the Hart class, which are inherently incapable of 55 adding amounts in many columns *seriatim* on a work-sheet, and cross-adding such amounts selectively in several groupings of registers.

This application is a continuation of my application Serial No. 504,501, filed December 24, 1930. 60

Other features and advantages will hereinafter appear.

In the accompanying drawings, Figure 1 is a perspective front top view of a novel machine embodying many vertical and 65 cross totalizers in one form. There may be employed less or more than the four cross-totalizers shown, according to the nature of the accounting to be performed.

Figure 2 is a sectional elevation, on a larger 70 scale, to illustrate details of the vertical totalizer mechanism.

Figure 3 is a sectional central elevation, from front to rear, showing a machine constructed according to the present invention in one form. 75

Figure 4 is a sectional detail, showing a full-stroke device for a cross-indexing mechanism.

Figure 5 is a diagrammatic sectional part of the machine, showing a method of performing 5 one kind of work thereon.

Figure 6 shows a method of performing another kind of work upon the machine illustrated at Figure 5.

Figure 7 is a perspective of a novel Siamese 10 digit-train operating a vertical master wheel and setting several cross-indexing pins.

Figure 8 is a perspective view showing a single 15 novel computing mechanism in which a master-wheel-operating Siamese train sets up auxiliary indexing devices preparatory to the subsequent 20 operation of a group of auxiliary registers. The pivoted key-operated member 29 is shown with its shoulder 29^a operating a universal bar 29^b which controls the operation of the carriage feed- 25 dogs 39 as the carriage 24 is driven by spring-barrel 39^a and strap 39^b, thereby controlling the denominational movements of the carriage 24, 40, and also selecting the denominations of the auxiliary indexing devices 75, controlled by the Siamese 30 digit-train, to correspond with the denominations of the dials 47 being actuated.

There is illustrated at Figure 5 a row of fourteen vertical totalizers, numbered 10 to 23, to travel step by step with the paper-carriage 24 of 30 an Underwood standard typewriter. The machine has numeral-keys 25 and alphabet-keys 26, all of the keys operating levers 27 to vibrate bell-crank 28, which throw type-bars 29 up against the platen 30. The platen carries a work-sheet 31, Figure 5, and is mounted on a platen-frame 32, that may be shifted up and down upon the letter-feeding carriage 24, by means of a shift-rail 33, for causing different types to print.

The carriage runs upon front and rear tracks 40 34, 35, and is propelled by a spring-barrel (not shown), and has a rack 36 meshing with a pinion 37 that is connected to an escapement-wheel 38. The latter is controlled by spacing dogs 39 at the operation of said keys, in a known manner.

Said vertical totalizers 10 to 23 are individually attachable and adjustable along a rack 40^a, upon a bar 40, fixed upon a truck 41 which travels with the paper-carriage 24. For connecting the truck to the carriage, the latter is 50 provided with a pair of forwardly-extending arms 42, having at their forward ends open slots to fit lugs 43 projecting from the truck 41. The truck, the totalizers, the indexing mechanism, the master wheel and many other devices are 55 disclosed in my co-pending application 286,218, filed June 18, 1928 (now Patent No. 1,971,544, dated August 28, 1934), and showing one totalizer, said application covering improvements pertaining to the general type of machine illustrated 60 in the one-totalizer patent to Kurowski, No. 1,710,775, of April 30, 1929. The totalizer is locked to the rack by latch 43^a.

The numeral-keys 25 operate novel Siamese 65 digit-trains, Figure 7. Each Siamese digit-train is made up of sub-trains. In the upper sub-trains are included pendent links 44, of which one is provided for each digit-key, and these links pull down cam-plates 45 that form a transverse row and are adapted to impart variable 70 movements to a master wheel 46. The master wheel is mounted upon the stationary framework of the machine, and is caused by the numeral-type-keys through said novel Siamese digit-trains to impart rotative movements to the 75 denominational wheel-trains in the totalizers, one

totalizer at a time. Each denominational wheel-train may include a gear 47, to mesh directly with the master wheel 46, and also a pinion 48 with a dial 49.

The plates 45 have an assortment of drive-cams 50, which swing down to operate pins 51, which are seen upon a row of vertical arms 52. The arms 52 rise from a transverse horizontal rock-shaft 53, whereby the latter is given different rocking movements by differing numeral-keys. 10

These movements of the shaft 53 are transmitted by a crank-arm 54 thereon through a link 55 to a universal sector 56. There is only one sector 56 for all the keys and all the totalizers; 15 and it drives the master wheel 46 through a clutch 57. The master wheel normally stands disconnected. When a numeral-key is depressed, the master wheel is first connected up and then rotated, as set forth in the two-totalizer co-pending application of Kurowski, 74,698, filed December 11, 1925 (now Patent No. 1,835,165, dated December 8, 1931), which discloses clutching members and other devices. 20

Each cam-plate 45 has a downwardly-projecting finger 58 to engage and depress a horizontal universal bar 59 that is mounted upon a rock-shaft 60 having arm 61, which throws up link 62 and rocks an arm 63 of a bell-crank pivoted at 64, and thereby swings bell-crank-arm 65. 30 Upon arm 65 is a pin 66, which operates the normally open clutch 57, to connect the master wheel with the Siamese digit-train.

It is to be perceived that by means of the keys 25 amounts may be typed in all of the vertical 35 columns 67 which fill the work-sheet 31, and that besides typing these amounts, said keys by means of their Siamese digit-trains will individually operate the master wheel 46 to an extent agreeing with the digit typed upon the 40 sheet. Thus the amounts typed are run into the primary totalizers 10 to 23, digit by digit, the described sub-indexing mechanism 44 to 65 being directly operated by the keys, each of which therefore completely adds a digit at each typing 45 operation.

Each of said novel Siamese digit-trains may simultaneously set from two to five (or even more) cross indexing devices or pins for the same digit that is being run into the single vertical 50 totalizer by the first sub-train and the master wheel. Said pins are set by the second sub-train. After the typing and primary adding of a number, the set indexing devices are run by power means into cross-computing totalizers, so 55 that the operation of many cross-computing totalizers concomitantly with any vertical totalizer may be effected, be the aid of the novel Siamese digit-trains, without ever causing the resistance of the key to the finger-touch to exceed appreciably that which is felt when merely operating a type-bar and the single master wheel. 60

The multiple sub-trains for the cross-computing totalizers, designated as A, B, C, D and E, are coupled to the vertical sub-trains to form 65 Siamese couplings that each of the digit-keys 25 may operate both the sub-trains. Each key performs three functions, viz., it prints a numeral, adds in a vertical totalizer, and sets up an index-pin for a cross-computer. 70

Each second sub-train of every Siamese coupling includes a pendent drive-link 70, having at its lower end a finger 71 which is depressed to rock an arm 72 upon a rock-shaft 73, of which there is one for each Siamese train. These rock- 75

shafts 13 respectively are connected with depressible cross-links 14, one for each digit, so that operation of any Siamese digit-train enables its cross-link 14 to press an index-pin 15. The 5 two sub-trains, in each instance, are coupled together by means of a coupler 15a, to form the single Siamese digit-train, Figure 7. Each Figure 7 Siamese train may be operated in any suitable way by a digit-key. Preferably each digit-key 10 operates a type-lever 27 which embodies the coupler-portion 15a, but this arrangement is not essential in all cases, nor is the train illustrated at Figure 7 the only form of Siamese digit-train that may be employed, and the key may be otherwise connected to operate first and second sub-trains for the purpose set forth.

These pin-bars are arranged in a horizontal row across the machine, and may form say five groups, one group for each of the totalizers or 20 registers A, B, C, D and E. The nine pins 15 on each bar are normally out of reach of the setting bars 14, but the pin-bars 16 for the cross-computers are advanced seriatim during the letter-feeding travel of the carriage 24, so that 25 the pins of the advanced bar or bars are brought within range of the depressible cross-bar 14.

The forward setting of the bars 16 for indexing purposes, is effected by the carriage 24, which not only positions the vertical totalizers, but also 30 carries setting dogs 17, 17A, 17B, 17C, 17D, 17E, each armed with a tooth 18, to lift the forward ends of jacks 19, one after another, as the carriage feeds along. Said jacks 19 are pivoted at 35 80, and operate thrust-links 81, which operate through a transposition mechanism 82, 83 to push pin-bars 16 forwardly one after another as the tappets 19 are raised, the denomination of the advanced pin-bars 16 being the same as that of the dial 49 which is about to be operated. 40 There is one tappet for each pin-bar of each group. Pin-bar and transposition mechanism is disclosed in the four-totalizer patent to Kupetz, 1,452,162, of April 17, 1923, but not in the specific relation disclosed herein. It will be seen 45 that practically no labor is put upon the key 25 by the cross-indexing mechanism just described, and that no cross-adding wheel is rotated by the depression of said key, so that the desired cross-computation may be performed without appreciably adding to the labor of operating the key, 50 which is one of the main objects of the invention.

At the completion of the operation of the novel Siamese digit-train (Figure 7), therefore, the primary dial 49 has been rotated according to 55 the type printed, and the corresponding cross-indexing pin 15 has been set, so that the machine is ready for operation of the succeeding Siamese digit-trains. In this manner, the key-typing of the amount in a column proceeds digit by digit, 60 while said amount is being run by the Siamese digit-trains into the vertical totalizer, said Siamese trains also setting up pins 15 in groups of pin-bars, inasmuch as the cross-bar 14 in the second sub-train is capable of setting a pin in 65 every group of pin-bars, at every key-depression. Five or more cross-computations may be performed, five cross-totalizers being included, since the cross-bar 14 can set five or more pins 15 without overburdening the type and master-wheel operating key 25.

After the amount is therefore typed in the column and added in the vertical totalizer, a motor 84, which is under the control of a cycling key 85, is operated to cause the cross-bar 86 of a 70 general operator to drive forwardly, by means

of the set pins 15, the racks 16 and the dials 85a of one or more of the cross-totalizers A, B, C, D, E, so that the precise amount is carried into each of said cross or subsidiary totalizers which had previously been carried into the vertical 5 totalizer.

The Siamese coupling of a vertically-adding master wheel to subsequently power-operated cross-adders by means of the digit-trains seen at Figure 7, is broadly new.

The carry-over mechanism of the cross-totalizers is indicated at 87, 88. The motor-controlling train includes a stem 89 and a latch 90, which is freed from a stop 91 in order to permit rotation of general operator 92. The latter includes a driving arm 93, which reciprocates slide 94 carrying cross-bar 86.

After the general operator on its forward stroke has advanced said subsidiary or cross-adding dials, it operates the carry-over mechanism upon its return stroke. At the conclusion thereof, a table 95 is automatically lifted, to restore all depressed pins 15, thus bringing the machine into condition for entering an amount into the next work-column.

The Figure 5 machine performs double cross-adding. The numbers typed in the first twelve columns on the work-sheet are added separately upon the vertical totalizers 10 to 21. At the same time cross-addition is performed of every line of 30 the numbers that are typed and added in the third, ninth and twelfth columns. This cross-adding is performed by running the amounts into cross-totalizer A. Also the numbers which are typed and added in the fifth, seventh, tenth 35 and eleventh columns are cross-added in totalizer B. At the conclusion of each line, therefore, the cross-total which appears in A may be copied in next to the last column on the work-sheet; while the cross-total that appears in B may be 40 copied in the last column on the work-sheet, this operation clearing said cross-totalizers A and B. When copying these cross-totals in the last two columns, they may be entered in totalizers 22 and 23, respectively, by means of said master 45 wheel 46.

At the conclusion of the typing of the page, the totals of the individual columns will appear in column-totalizers 10 to 21, respectively, while 50 22 will show the total of all amounts typed in the third, ninth and twelfth columns, while the totalizer 23 will show the total of all amounts typed in the fifth, seventh, tenth and eleventh columns.

According to the foregoing, at every line a certain partial cross-total is entered in 22, and another partial cross-total is entered in 23. These partial cross-totals are also run into cross-totalizer C, which, at the conclusion of the typing of the sheet, shows the gross total of all of the 60 cross-added amounts.

After finishing the page, the amount that shows in vertical totalizer 22 may be copied into the next to the last column, and at the same time subtracted out of both 22 and cross-totalizer C. 65 Said totalizer C will then display the same amount which is displayed in totalizer 23. Said amount may then be copied into the last column, simultaneously clearing the totalizers 23 and C. This proves that the amounts have been correctly 70 copied line by line from cross-totalizers A and B into the last two columns of the work-sheet.

At the completion of each line, star-keys may be printed in the last two columns, to indicate that cross-totalizers A and B stand at zero. At 75

the conclusion of the copying of the totals in the last column, at the completion of the sheet, a star-key may also be printed in the last column, to indicate that the totalizer C stands at zero, and therefore that the copying has been correctly performed.

The totals of all the amounts entered into the vertical totalizers 10 to 21 may be concomitantly run into cross-totalizer D, which, therefore, at the conclusion of the page, shows a grand total of all the amounts typed thereon. This grand total may then be copied at the bottom of the page, and at the same time subtracted out of D, whereupon the star-key may be printed.

15 The aforesaid computation is therefore so intricate as to include vertical adding in all of the numerous columns, partial cross-adding of amounts in certain columns, other partial cross-adding of amounts in certain other columns, accumulation of cross-added amounts in totalizers 22 and 23, entry of all cross-added amounts in cross-totalizer C, typing of totals of the two kinds of cross-adding in the last two columns on the work-sheet, the proving of the correctness of 20 copying by means of cross-totalizer C, and copying of grand total from cross-totalizer D.

At Figure 5 there are shown five groups of jacks 79, corresponding respectively with the cross-totalizers A, B, C, D and E. The jack-groups have assorted lengths, and the dogs 77 are of corresponding lengths, whereby it is provided that certain dogs will operate certain jacks and not others. The shortest dogs 77^E are capable of operating only the longest jacks 79^E, the same 35 being associated with the grand totalizer D. The longest dogs operate only the group of shortest jacks 79^A, which are associated with the first cross-totalizer A. Other dogs, according to their lengths, operate the remaining groups of jacks 40 79^B and 79^C. The jacks are all adjustable along a rack 96.

In the three-totalizer machine disclosed in the Hart patent, 1,190,171, of July 4, 1916, there are shown a group of long jacks and a group of short jacks, and a group of intermediate jacks, together with adjustable short, long and medium dogs; and the explanation in said patent of the method of denominational controlling the three Hart totalizers at the front of the machine, by means 45 of said assorted jacks and assorted dogs at the rear of the paper-carriage, will enable the above description of the operation of the jacks, etc., to be understood. Where it is required that the same dog shall operate two sets of jacks (one set 50 after another) it is armed with two teeth 78^A and 78^D.

Means such as shown in said Hart patent may be used for lifting the table 95 automatically at the conclusion of the cycling of the general operator, thereby restoring all of the subsidiary indexing pins 75.

The vertical totalizers are operable subtractively, being for this purpose controlled by keys 97, which operate a rock-shaft 98 having thereon 65 an arm 99 to shift a back-gear 100 into mesh with a companion gear 101, said rock-shaft 98 also having a pendent arm 102, to shift sector 56 into mesh with back-gear 100. The master wheel 46 may therefore be caused to rotate reversely 70 at the operation of the type-keys 25.

To cause the cross-totalizers to subtract, there is provided a subtraction-setting mechanism, including a key 103, which presses back a rod 104 to operate a subtraction-setting rock-arm 105, rock-shaft 106, slide 107 and rock-arms 108, 109, to

cause the indexing mechanism to operate by setting complementary pins, as in said three-totalizer machines set forth in said Hart patent, and in various patents that have been granted for improvements thereon.

The clearing of any vertical totalizer may be effected by setting the same to subtraction, and then copying upon the work-sheet the number which appears in the totalizer. Any cross-totalizer may be cleared independently or together 10 with the vertical totalizer.

If it is desired to clear a cross-totalizer without affecting the master wheel of the primary totalizers, said master wheel may be silenced at the operation of the type-keys. This silencing 15 provision is in the nature of a key-mechanism 110. In the key-driven one-totalizer master-wheel machine shown in said Thieme application, 286,218, this key 110 is shown operating a rock-shaft 111, having a crank-arm and pin 112, to 20 which is pivoted the upper end of a pendent link 113, which at its bottom has a cam at 114, to press to one side the link 44, whereby slot 115 in the link is withdrawn from pin 116 upon operating arm 117, which is fixed to the sub-train coupling portion of the type-key-lever 21. These and other devices taken from co-pending applications are used here illustratively only, and are not made the subject-matter of specific claims herein. The primary totalizers being therefore 30 silenced by the manipulation of the key 110, it is provided that any one or more cross-totalizers may be operated subtractively or otherwise by the use of the digit-keys 25 without causing the novel Siamese digit-trains to affect any primary 35 totalizer.

It being sometimes desired to silence all of the cross-totalizers, without affecting the operation of the primary totalizers by the novel Siamese digit-trains, there is provided a silencing key or 40 lever 118, which operates a silencing train substantially like that shown in said Kupetz Patent No. 1,452,162. A lever, 119, 120 presses back a link 121 and causes a bell-crank 122, 123, to rock an arm 124, and thereby throw out an arm 125 45 that carries a supporting roll 126, whose normal function is to hold up any dog 77 that may be passing through the zone. There are an arm 125 and roll 126 for every subsidiary totalizer, and they are operated simultaneously. It will 50 thus be seen that, if need arises, any of the vertical totalizers may be operated by the novel trains for addition or subtraction, at the depression of the digit-typing keys 25, while no computation is effected by the novel Siamese 55 digit-trains in any cross-totalizer. The disabling arm 125 is held out of use by a latch 127, and this may be released by means of a connection to the general operator, including arm 128, sector 129 and pinion 130, meshing with 60 general operator rack 94.

Sector 129 is mounted on a shaft 131, having a cam 132 to lift a sliding arm 133 and thereby unlatch 121, as set forth in said Kupetz patent, 65 1,452,162.

Every cross-totalizer may be provided with a star-printing mechanism including a key 134 and key-lock devices 134^a. Mechanism of this kind is set forth in the one-totalizer patent to 70 Hoyt, No. 1,256,309, of February 12, 1918.

The cross-totalizer mechanism may also be provided with error-key 135, to cause the operation at will of platforms 95 that restore set index-pins 75; these tables 95 being also operable 75

by the general operator at the conclusion of its cycling.

In the event of a digit-key being struck and its type printed erroneously, whereby the novel Siamese digit-train is caused to carry said erroneous digit into the vertical totalizer and to set up corresponding pins for the cross-totalizers, the operator may take the following steps: first, the cycling key 85 may be operated to carry the erroneous digit into the cross-totalizers. Then the erroneous number may be erased from the work-sheet. Then a non-print device 136 may be put into position, and both the vertical and cross indexing mechanism may be set for subtraction. The erroneously struck digit-key may then be depressed a second time, and its amount may be duly run out of the vertical and cross totalizers. Then the operator may remove the non-print device 136 from working position, and strike the correct digit-key, which may be duly run into the various totalizers by a Siamese digit-train and the cycling mechanism in the manner already explained.

The carriage is propelled by a spring (not shown) in a manner usual in Underwood type-writers; and it is freed and arrested intermittently, by dogs 39, in position to bring a denomination gear-train 41 into proper mesh with the master wheel 46, and also to bring one or more of the jacks 79 to working positions; that is, one or more jacks will become poised upon the tops of the teeth 78 of the denomination-selecting dogs 77.

Relative adjustment between the totalizer-truck 41 and the rack or truck 96 is provided to adjust either truck 41 or 96 independently of the other. This secures accurate positioning of the denominational wheel-trains relatively to the master wheel 46, and also accurate positioning of the dog-teeth 78 relatively to the jacks 79. Both adjustments are properly made with reference to the printing point of the type-writer, which is indicated at 29 in Figure 1.

The adjustment of the truck 41 is provided for by means of an eccentric screw 137, upon which the square projecting washers 43 are mounted; the eccentricity permitting the washers to be moved to the right or left sufficiently to correct any lateral misadjustment of the truck 41 relatively to master wheel 46; and the dog-carrier rack 96 is also adjustable endwise, having a tip 138 threaded through the end of an arm 139, provided upon carriage 24. Nuts 140 may be manipulated for adjusting the rack 96 endwise, and for securing the same. The opposite end of the rack is flattened at 141 to fit in a narrow hole in the opposite end 142 of the carriage. This permits endwise adjustment of the rack 96, to cause the teeth 78 to complete the lifting 60 of the jacks just as the carriage is arrested by the dogs 39. Thus accurate co-operative working is secured of the subsidiary or cross totalizers and the primary or vertical totalizers at each step of the common carriage.

Each key-lever 27 is provided with three pins, one of them 143 being used for driving the type-bar 29, and being fixed upon a mount 144, which is pivoted at 145 to the key-lever, so that the mount and pin may be adjusted by independent manipulation of screws 146, threaded into the mount and bearing upon the lower edge of the key-lever. Thus it is provided that the type is brought to the printing point promptly after the conclusion of the operation of the novel Siamese digit-train whose sub-trains are coupled by the

key-lever, the sub-trains ramifying up and down from said key-lever.

The master-wheel-operating pin 116 is fixed upon mount 117, pivoted at 147 to the coupling-portion 75^a of the key-lever and similarly adjustable.

The subsidiary indexing is effected by a pin 148 upon mount 149 provided upon the coupling-portion 75^a of the lever 27, this mount being similarly adjustable by screws. 10

Thus each digit sub-train is adjustable relatively to its companion sub-train, whereby the master-wheel operation and also the subsidiary pin-indexing operation are timed with accuracy with reference to each other, and proper timing 15 is also effected with reference to the impression of the type upon the work-sheet.

The foregoing construction tends to avoid errors of computation through faulty manipulation of the digit-type-key 25. This key is 20 somewhat harder to operate than alphabet-key 26, because by means of its Siamese train it has to set in motion the master wheel, as well as the digit sub-train and the indexing device operated thereby, plus the denomination-wheel train 41. 25 The operation of the master wheel, however, is completed before the type strikes the paper, and before the key 25 concludes its printing stroke; the pin 51, at the concluding operation of the key-stroke, occupying a dwell 150 at the end of 30 the slot 50, so that the last portion of the down stroke of the key and Siamese digit-train is idle, so far as the master wheel is concerned.

At this concluding stage, therefore, the Siamese digit-train has no work to do in connection with 35 the vertical totalizer, and this is the time when the stem 71 of the digit-train is engaged in operating the arm 72, which, however, is easily operated, and does not appreciably load the key 25. In fact, the hand of the operator, as well as the 40 key and type-bar and other parts of the mechanism, are at this moment in motion, and the slight resistance of the pin-setting sub-train is easily overcome by the descending key, and the complete setting of the pins is insured, because 45 at this time the Siamese digit-train is relieved of the burden of rotating the master wheel.

As a safeguard against error, due to faulty manipulation of the key 25, there may be employed such a full-stroke device as is disclosed 50 in the Hanson patent, 876,959, of January 21, 1908, which assures a complete down-stroke of the key, and then assures a complete up-stroke of the key, before another key can be manipulated; inasmuch as any depressed key 25 prevents the operation of other keys by means of a key-lock train 151, such as shown for example in the one-totalizer patent to Hanson, No. 1,278,812, of September 10, 1918.

In place of the device seen in said Hanson 60 patent, there may be employed, if desired, a pendulum link 152 having opposite teeth 153, 154 to co-operate with a full-stroke spring-pawl 155. In this type of full-stroke device, the indexing stem 152 is formed with a succession of bends, 65 which project forwardly from the stem at points about midway of its height, so as to serve roughly as teeth 153, 154, over which spring-pawl 155 rides idly, whether the stem 152 is ascending or descending. The pawl 155 is provided with a 70 double-acting spring 155^a, which tends to hold it in midway position. This pawl 155 is always idle, except that it will not permit the digit-key 25 to rise unless it has made a full down stroke. Neither will it permit the key to be depressed 75

unless it has completed its up stroke. Both these results are accomplished by the tooth of the pawl catching in a diagonal notch or slot 155^b formed between the aforesaid teeth 153, 154 that project from opposite sides of the stem or link. Premature attempts to move the stem either up or down will result in the pawl-tooth catching in the notch 155^b, thus making it necessary for the operator to complete the original stroke of the stem, in order to free the pawl. Each stem at its bottom co-operates with a row of tumblers 151 to lock all of the numeral-keys.

The supplemental key-locking mechanism 153, etc., may be provided because when the digit-trains are disconnected from the master wheel, the main key-locking mechanism is also disconnected; but the supplemental key-locking mechanism would operate. This supplemental key-locking mechanism is also hooked up for other locking devices, as, for example, when a key is depressed, the automatic motor-trip cannot operate until the key is fully returned.

When one numeral-key is depressed, the supplemental key-locking mechanism becomes effective to prevent a second numeral-key from being fully depressed; but the second key can be depressed about one-eighth of an inch, or sufficient to start the rotation of the master wheel, thus making the main full-stroke mechanism necessary in order not to jam the machine. For the master-wheel indexing means, there may be employed a ratchet 160 on plate or sector 45, to mesh with a ratchet-blade 161, to insure full-stroke of the sector 45 in each denomination; and this full-stroke device may be disconnected from the keys 25 through the disconnection of the links 44 of the digit-trains.

The carriage may be controlled by tabulating mechanism, including keys 165, which operate selectively denomination-stops 166, by raising them into the path of column-stops 167 mounted upon carriage-rack 168.

Certain of the column-stops may carry tappets 169, to operate trains 170, 171, 172, to set the machine to subtraction automatically as the carriage enters the particular computing zone, which is determined by said column-stop 167.

One or more of the column-stops 167 may also be provided with a tappet 175, for operating a train 176, 177, to cause automatic operation of motor 84 to drive the general operator 93, 94, 86 at the egress of the carriage from that computing zone which is determined by the specified column-stop 167.

The type-bar 29, as shown, is provided with upper and lower types, and the platen is made shiftable up and down by means of rail 33 and arm 180 on rock-shaft 181, the arm 180 being operated by bell-crank-lever 182 provided with a shift-key 183. When the platen 32 is shifted up, an arm 184, extending back from rock-shaft 181, operates upon a cam 185, to swing a rock-shaft 186, together with its arm 125 and roll 126, the latter being swung backwardly to idle position, permitting the indexing dog-carrier 77 to drop, so that the pin-setting devices are silenced when an upper-case type is being printed.

At the same time, this shift-key 183 may disconnect the master wheel operating sub-trains from the digit-keys 25, as for example by means of a link 187 disclosed in my co-pending one-totalizer application, No. 286,218, filed June 18, 1928; said link being connected at its upper end to a bell-crank 188, to pull the same down, so that a cam 189 that is formed upon said bell-

crank will cam endwise a slide 190, the latter having slots to form a comb for guiding the sub-train links 44, and the endwise movement of the slide 190 swinging said links laterally, to carry them out of engagement with the drive-pins 116. This slide 190 is also operable by the disconnect key 110 of the train 111, 112 and 113.

The carriage may be returned by power, through the key-mechanism 191.

As another example, all of the numbers that are typed in each column may be added in its individual vertical totalizer, and at the same time cross-adding may be done in say the right-hand cross-adder E. There may be run into the next cross-adder D all of the amounts that are typed in all of the columns, so that at the conclusion of typing the sheet, the grand total will show at D; while each vertical totalizer will show the total of its own column. Then the vertical totalizers may be set to subtraction, and the totals shown therein may be typed at the bottoms of their respective columns, and at the same time each total may be cross-accumulated in totalizer C. Accordingly at the end of this operation the vertical totalizers will all show zero, and each of C and D will show the same amount as the other, since, while subtracting these amounts from the vertical totalizers, they are being added into totalizer C. Therefore at the end of the operation, each of the two registers C and D shows the same grand total. The cross-adding mechanism may now be set for subtraction, and this grand total may be copied onto the work-sheet, and then the star may be printed, thereby proving accuracy throughout. The cross-totalizers C, D, E may all be disconnected during the copying of the totals from the vertical totalizers into totalizer B. Both totalizers B and D are in operation during the final copying of the grand total, and both become restored to zero, and star-signs may be printed.

At Figure 6 a still more intricate computation may be readily performed by means of a form of this invention, that is illustrated at Figure 5, upon the novel machine. This employs all five of the cross-footing totalizers A, B, C, D and E, as well as fourteen totalizers in which the master-member 46 adds vertically; and each vertical totalizer may have nine dials. The disposition of the vertical totalizers must agree with the location of the respective amount columns on work-sheet 192. Proof of accuracy is secured in connection with cross-adding, and also in connection with vertical addition. The totalizers 10-23 show the totals of amounts entered in the fourteen amount-columns on the form. Upon the main work-sheet 192, is placed an individual investment ledger-card 193, which is posted simultaneously with a portion of the work done upon the main sheet 192.

First. As the first operation in each line of typing, the old balance of the particular investment ledger-card that is affected, is typed in the "Old balance" column at the left-hand edge of the work-sheet 192. This amount is duly added, for cross-footing, in cross-adder A. The cross-footing operations are indicated by letters and signs under the bottom of the sheet 192. This amount is also vertically accumulated in totalizer 10.

Second. The date, reference number and description of the transaction are written in the second, third and fourth columns of the work-sheet.

Third. The par value is calculated mentally, and its amount is entered in the column cap-

tioned "Par value," but it does not enter into any computation.

Fourth. Debits or credits, depending upon the transaction involved, are entered in either one or the other of the next two columns, the first headed "Debit," and the second "Credit." Both debits and credits are entered in cross-footing totalizers A, B and E. At the same time corresponding entries are made in vertical totalizers 11 and 12. It may be observed that after all cross-footing is completed for each line of writing, the respective amounts remain accumulated in the vertical totalizers, each of which may hence constantly show the total of the entries in its own column. The last line at bottom of Figure 6 indicates accumulations in the vertical totalizers.

Fifth. The new balance of the individual investment ledger-card 193 is indicated by cross-footer A, and when this amount is copied therefrom correctly in the "New balance" column, said cross-footer A is cleared, and a star or sign is printed by means of key 134, proving correctness of the amount of the new balance. This completes the typing and computation, so far as the individual investment ledger-card 193 is concerned, except that the amount of the new balance is vertically accumulated in totalizer 13.

Sixth. The previous balance of the investment control is then ascertained and typed in the column marked "Old balance" under the caption "Investment control," and is run into the cross-adders B and E. It is also accumulated in vertical totalizer 14.

Seventh. At this point, the cross-totalizer B indicates the new balance of the "Investment control," and this is typed in the next column, and thereby cross-footer B is cleared, and a proof-sign is printed. This new balance is simultaneously entered as a subtraction in cross-totalizer D. It is also accumulated in vertical totalizer 15.

Eighth. Either a credit or a debit affecting the Corpus may be entered in one column, which is captioned "Cr." or "Dr." The credit or debit is entered at each line of typing in cross-footer C, and also in cross-footer E; the debit being added, or the credit being subtracted. At the same time each debit is added or each credit is subtracted in vertical totalizer 16.

Ninth. The old balance under "Corpus" is typed in the "Old balance" column, and subtracted out of cross-totalizers C and E. It is also accumulated in vertical totalizer 17.

Tenth. The new balance is then copied in the indicated column under "Corpus," this amount being copied from cross-footer C, which thereby becomes cleared, permitting a proof-sign to be printed. The amount of the new balance is simultaneously added in cross-footer D, and is accumulated in vertical totalizer 18.

Eleventh. As a result of the seventh and tenth operations, the balance of the principal cash has been mechanically computed, and is exhibited in cross-footer D. The amount is copied from D into the column headed "Principal cash," and at the same time it is subtracted from D, which is cleared, and a proof-sign is printed. The amount is also accumulated in totalizer 19.

Twelfth. The amount is copied from "Principal cash" into the next column, captioned "Proof." If the work has been done correctly, the cross-footer E will be cleared, and a proof-sign can be printed. This amount is also accumulated in vertical totalizer 20.

Thirteenth. Upon the same line of typing, with the same date and with appropriate description,

the amount of income may be entered in the column "Cr." or "Dr." under the caption "Income." This amount will be run into totalizer E, being either added or subtracted as required. It is also added or subtracted in vertical totalizer 21.

Fourteenth. The old balance may be then typed in the next column, and added in totalizer E, which will then show the new balance. At the same time this amount is accumulated in vertical totalizer 22.

Fifteenth. The same old balance may then be subtracted from totalizer E by copying it into the "Old balance" column, whereupon the proof-sign may be printed. This amount is also accumulated in vertical totalizer 23.

The foregoing operations take place at the typing of every line.

Thus in typing each line, it will be seen that in A the new balance of the individual investment ledger-card is cross-footed. In B the new balance of the investment control is computed. In C the new balance of the corpus is added to the new balance in income cash. The balance of the principal cash is computed in D. The cross-footer E insures mechanical proof of accuracy of computation in each line.

It has been seen that in every line the amounts are duly entered by the master wheel or other master member 46 in the appropriate vertical totalizers, of which one is assigned for each column in which there is to be vertical accumulation. When the work seen at Figure 6 is being performed upon the machine seen on a smaller scale at Figure 5, the totalizers 10 to 23 must be located in the same zones as their respective columns which appear upon the work-sheet 192.

At the conclusion of the typing and cross-footing, as aforesaid, of the items upon a page, the cross-totalizers A to E will all show zero; but the totalizers 10 to 23 will each show the footing of its assigned column. These vertical footings may be used in accomplishing a variety of purposes. One purpose, for illustration, may be in the nature of proving accuracy. The operator is moreover enabled to copy the vertical totals at the ends of the columns. These vertical totals may be used in various ways, in connection with the method of accounting prevailing in any establishment.

There are numbered in the bottom line at Figure 6 the primary totalizers, in which all of the amounts entered in their respective columns are added vertically.

Primary totalizer 10, therefore, shows the total of the old balances appearing in the first column. Primary totalizer 11 shows the total of the corresponding debits, and totalizer 12 shows a total of the corresponding credits; while totalizer 13 shows the total of all the corresponding new balances in the columns in which these numbers appear in said last line on Figure 6.

The operator now copies upon the work-sheet the total of old balances that is shown by totalizer 10, subtracting it from said totalizer, and at the same time adds it in cross-totalizer A.

The operator then copies at the bottom of the next debit column, the total which appears in totalizer 11, subtracting it from the latter, and at the same time adds said amount in totalizer A. Incidentally, the same amount is also stored in each of cross-totalizers B and E, for purposes which will be later explained in connection with subsequent computations.

Primary totalizer 12 shows the total of the

adjacent "Credit" column, and this total is copied at the foot of said column, and at the same time is subtracted out of 12, and also subtracted out of totalizer A. For future use, it is also incidentally subtracted out of each of totalizers B and E, and this will presently be explained. Cross-totalizer A now should exhibit the same amount as is exhibited in vertical totalizer 13. This amount may then be copied at the foot of 10 the first "New balance" column, thus clearing totalizers 13 and A, and enabling the proof-sign to be printed.

The next two totalizers 14 and 15 have been used respectively for vertically adding the old 15 balances and the new balances under the caption "Investment control," so that it will be understood that 14 shows the total of the old balances, and 15 shows the total of the new balances. From totalizer 14 the total is copied at the foot 20 of the "Old balance" column, and at the same time it is subtracted out of 14 and also added into cross-totalizer B. At the same time it is incidentally added into cross-totalizer E, to take part in a subsequent operation.

25 The total of the new balances under "Investment control" is seen in totalizer 15, and this total should agree with the total that is now seen in cross-totalizer B. This total may now be typed at the foot of this "New balance" column, 30 and at the same time subtracted out of totalizers 15 and B, clearing both of them, and permitting the printing of the accuracy or proof sign.

Proceeding now to the three columns grouped under the heading "Corpus," the vertical totals 35 of which appear in totalizers 16, 17 and 18, respectively, the operator may proceed to copy at the foot of the first column the total from 16, at the same time subtracting it out of totalizer 16 and adding it in totalizer C. It is also at this 40 time incidentally added in totalizer E for future use. The operator then copies the total appearing in 17 at the bottom of this "Old balance" column, and at the same time subtracts the amount out of 17 and out of C, and also out of 45 E. The amount, which is thus made to appear in totalizer C, should equal the total which appears in 18. This amount may then be typed at the bottom of this "New balance" column, and at the same time subtracted out of 18 and C, permitting 50 the proof-sign to be printed.

The next totalizer 19 shows the total of all the items of "Principal cash." This total is now to be copied upon the work-sheet, and subtracted from 19. It is also subtracted from cross-totalizer D, thereby clearing the same. It will be recalled that the total copied from vertical totalizer 55 15 has been subtracted from D, while the total shown by totalizer 18 has been added to D, thereby computing the difference between the totals 60 of these two "New balance" columns. This difference should equal the total of the "Principal cash" column; and said total can be subtracted out of 19 and also out of D, bringing the latter to zero, and permitting the proof-sign to be 65 printed.

Primary totalizer 20 shows the total of the items which are entered in the column captioned "Proof," which proof items have been made up by cross-fooding in each line the items appearing in several previous columns, as above explained. The total of this "Proof" column should appear in totalizer 20 equal to the total in the "Principal cash" column, which it will be recalled was obtained by other methods. The 75 total of the items in the "Proof" column may be

copied at the bottom of the column, and at the same time subtracted from 20 and from cross-totalizer E, permitting the printing of the proof-sign.

The footings of the last three columns on the 5 work-sheet are shown in totalizers 21, 22 and 23, respectively.

The footing is copied and subtracted from totalizer 21, and at the same time it may be entered in any cross-footing totalizer, as for example E.

The footing is then copied from 22 onto the work-sheet, and also entered into the same totalizer E, which should then show the same total that is shown by totalizer 23, from which 15 it may be subtracted, and at the same time subtracting it from E, and bringing the latter to zero, thus permitting the printing of the proof-sign.

It may be observed, in review, that if any error 20 in any way creeps into the computing in the various columns, such error is bound to result in a discrepancy showing between the subsidiary registers D and E. This is because (at the operation of entering the footings and proving the 25 computations), items are entered into D from three columns, while items are entered into E from six other columns.

The invention is obviously not limited to any 30 one of the usual ways in which shifting of any totalizer to subtraction is performed.

From this description of the operation at Figure 6, it will be perceived that one of the aims of the invention when used for some classes of work, is in the direction of preventing an undetected 35 error from being made in any computation on the completed work-sheet, whether such error arises from mistakes of the operator or from faulty operation of the computing mechanism.

It will be understood that the machine is hybrid 40 because it embodies a master-wheel mechanism which effects complete computation at the operation of the type-key, and also embodies an incongruous element in the form of deferred-operation computing mechanism, in which index- 45 devices are set at the key-operations, but computation is not controlled thereby simultaneously with the master-wheel computation but is deferred. The mere setting of an index-device at the key-operation, is incongruous with effecting a complete computation simultaneously by the same key. The incongruous elements are co-ordinated digitally by means of the hybrid Siamese trains and denominational by means of the hybrid carriage, which presents the denominational gear-trains one by one to the master-wheel for complete computation, while co-ordinating with that operation the denominational selection of deferred-operation indexing devices. Hence at the depression of a key not only is a 50 complete computation effected but an index-device is also coordinately set up for deferred computation of the same number.

It will thus be seen that by the novel combined typewriting and hybrid accounting machine, there may be effected at the typing operation (1) a complete computation by means of the master-wheel, or (2) an amount may be indexed for deferred computation thereof, or (3) an amount may be completely computed and incongruously the same amount may be simultaneously indexed, for the purpose of effecting deferred computation thereof; that the machine has a hybrid carriage in that it presents the master-wheel to the totalizers successively, and to 55 70 75

the dial-wheels in each totalizer denominational or serially, for complete computation, and also coordinatively therewith automatically makes selection of any number of cross-registers 5 up to five or more, and also controls the denominational presentation of index-pins to digit-setting devices for the incongruous operation of the selected register-indexing mechanisms by the keys; that the machine has as a main element a 10 master-wheel mechanism, controlled by the Siamese trains that extend from the keys, whereby master-wheel computation is completed directly at the key-operation; that vertical totalizers may be shifted or moved into and out of 15 position for operation serially by the master-wheel; that the machine also includes as the element that is incongruous with said master-wheel mechanism, a group of deferred-operation cross-adding registers, the same being incongruous because 20 they are merely indexed at the key-operations, while the master-wheel effects a complete computation, one digit at a time; and being further incongruous because the entire amount (of many digits) is run at one operation into the 25 cross-adding registers, while the dials of the vertical totalizers remain stationary; that the direct-operation master-wheel mechanism is supplemented by the deferred-operation cross-adding register-mechanism, being coordinated 30 therewith (1) digitally by the Siamese trains and (2) denominational by the hybrid carriage, which automatically selects different groupings of registers to combine with different individual column-totalizers; that settable means are provided 35 for bringing any cross-adding register automatically into indexable control by the Siamese trains and hybrid carriage; that any cross-adding register may be operated independently of the others, and may also be operated independently 40 of the vertical totalizers; and that the indexing is effected selectively by the co-operation of the hybrid Siamese trains and hybrid carriage for the deferred-operation registers, either independently of the vertical totalizers or during the direct complete computation of an amount by 45 said trains and carriage in any selected vertical totalizer.

I am aware of the well-known standard Underwood bookkeeping machine which is shown for example in the Hart Patent 1,382,286. In this 50 class of machine, there are key-operated trains, which operate indexing devices for all totalizers at once. The trains have to be light, in order to operate easily, and they are therefore weak, so that any attempt to increase the number of totalizers beyond those shown in the Hart patent 55 would result in these key-trains being found to be too weak and to fail to operate accurately. The experience of a score of years of manufacture has established seven as being the limit of totalizers 60 that can be successfully controlled by the key-trains of said Underwood bookkeeping machine, since each key-train must be long enough to spread across all seven of the totalizer-mechanisms. However, in the face of this limitation, it 65 has been sought to increase the capacity of the Underwood machine by splitting each totalizer into two separate totalizers, without increasing the dimensions of the machine, and without altering the key-mechanism. Each split totalizer, 70 however, has only half of the original capacity. Upon the advent of the present invention, the production of split totalizers was abandoned.

The Underwood class of machine illustrated in 75 the Hart patent cannot satisfy the demand for a

machine having a great number of totalizers. Still less can it meet the demand for a machine either capable of numberless combinations of numerous selective groups of vertical totalizers with a large number of cross-adders, one for each of said vertical groups, or even capable of combining a few cross-adders with a great number of vertical totalizers, or of co-operatively associating either a large number or a moderate number of vertical totalizers with a large number of cross-adders. The Underwood seven-totalizer machine is physically limited to double cross-addition, with the necessary vertical addition of the same amounts. 5

The seven-register Underwood machine is of course wholly incapable of the requisite performance. While every register in a seven-register machine is inherently capable of cross-adding, still it is a practical consideration that where all (or all but one) of the seven must be 10 devoted to vertical addition, the machine becomes hopelessly crippled for simultaneously cross-adding in four places. The problem faced and heretofore unsolved by experts was just this, that to use the registers for vertical addition led 15 to crippling the machine for the performance of the desired double and triple cross-adding simultaneously with the vertical addition. 20

I am aware of the K'Burg Patent 1,370,022, of 25 March 1, 1921, showing a standard Underwood bookkeeping machine adapted for a centralized system of bookkeeping, which brings together on one work-sheet the accounts of several different insurance companies; but no cross-adding is sought to be performed. 30

Variations may be resorted to within the scope 35 of the invention, and portions of the improvements may be used without others.

Having thus described my invention, I claim:

1. A combined typewriter and computing 40 machine comprising a set of numeral type bars, a single set of numeral keys associated with said type bars, a plurality of key-operated vertical totalizers of the master-wheel actuated type, a plurality of cross totalizers of the index pin type, 45 means for selectively associating any of said key-operated vertical totalizers with any of said cross totalizers, and means controlled by any selected numeral key for operating its associated type bar and running up the numeral in any selected vertical totalizer and simultaneously setting the indexing mechanism of any selected cross totalizer. 50

2. A combined typewriter and computing machine comprising a set of nine digit type keys, 55 a key-operable master wheel, a plurality of vertical totalizers operable by the master wheel, a plurality of cross totalizers having key-settable index-pin mechanism, carriage mechanism for selectively associating any of said key-operated 60 vertical totalizers with the master wheel and concomitantly selecting any one or more of said cross totalizers for indexing, and devices enabling every key to control digitally both the master wheel and the index-pin mechanism. 65

3. In a computing machine, complete column-adding main mechanism of the master-wheel class, a cross-adding mechanism of the index-pin class, a single set of numeral keys, and means operatively connecting each of said keys with the 70 column-adding mechanism and with the cross-adding mechanism, whereby upon the depression of any key, said index-pin devices are set simultaneously with the column-adding operation of said main mechanism. 75

4. In an accounting machine, a carriage, a single set of numeral keys controlling said carriage, a plurality of vertical totalizers of the master-wheel-actuated type, means operatively connecting each of said keys to the master wheel, whereby the latter is operated during only a primary portion of the down-stroke of a selected key, a plurality of cross totalizers of the index-pin type, means operatively connected to each of said 10 keys for setting the index pins of said cross totalizers during only the last portion of the down-stroke of said selected key, while said master wheel remains stationary, type bars operable by said keys throughout their strokes, and each 15 effective to print at the conclusion of said index-pin setting operation, and means for cycling said cross totalizers.

5. In an accounting machine, a letter-feeding carriage, a single set of ten digit-type-operating 20 keys, a plurality of vertical totalizers of the master-wheel-actuated type for various zones on a worksheet, a plurality of cross registers, indexing mechanisms therefor, means connected to said keys for operating the master wheel of said 25 vertical totalizers during the typing operation, a second means connected to said keys for operating the indexing mechanisms of said cross registers and coordinating the same with said vertical totalizers, adjustable selecting means on said 30 carriage to enable any one or more of said cross register indexing mechanisms to be brought selec-

tively into use and indexed, whereby cross-footing may be performed line by line in the cross registers of the amounts already entered seriatim in the vertical totalizers, and separate means for cycling said cross registers under the control of 5 said indexing mechanisms while the keys remain stationary.

6. In an accounting machine, a plurality of column totalizers, a plurality of systems of set-table index pins, a single set of ten digit-type 10 keys, nine digit-trains driven by said keys and including means to set said pins, a carriage controlled by said keys, means on said carriage for automatically coordinating various groupings of systems of index pins with each successive column 15 totalizer, means to cooperate with said carriage and said digit-trains to set selectively index pins of corresponding denominations in said systems, a master wheel also operated by any of said digit trains coordinatively with the setting of index 20 pins by that train, each column totalizer having denominational wheels cooperative seriatim with said master wheel, means on the carriage to present selectively to the master wheel a totalizer kheel of a denomination automatically coordinated to the selected index pins by said carriage, a plurality of cross registers associated with said 25 systems of index pins, and means for cycling said registers according to the settings of said index pins.

OTTO THIEME.
